SNAG RELEASE FOR FISHING TACKLE

Perry G. Snyder, Youngstown, Ohio

Application September 30, 1947, Serial No. 141,666

Term of patent 7 years

(Cl. D31—4)

To all whom it may concern:

Be it known that I, Perry G. Snyder, a citizen of the United States, residing at Youngstown, in the county of Mahoning and State of Ohio, have invented a new, original, and ornamental Design for a Snag Release for Fishing Tackle, of which the following is a specification, reference being had to the accompanying drawing, forming a part thereof.

Figure 1 is a front view of the snag release for fishing tackle, showing my new design.

Figure 2 is a bottom view of the snag release for fishing tackle, showing my new design.

Figure 3 is a side view of the snag release for fishing tackle, showing my new design.

The back (not shown) is substantially plain.

I claim:

The ornamental design for a snag release for fishing tackle, as shown and described.

PERRY G. SNYDER.
